UNITED STATES PATENT OFFICE.

CHARLES ELMER BERTELS, OF WILKESBARRE, PENNSYLVANIA.

CUSPIDOR.

SPECIFICATION forming part of Letters Patent No. 749,019, dated January 5, 1904.

Application filed August 21, 1902, Serial No. 120,545. (No model.)

To all whom it may concern:

Be it known that I, CHARLES ELMER BERTELS, a citizen of the United States, residing at Wilkesbarre, in the county of Luzerne and State of Pennsylvania, have invented a new and useful Cuspidor, of which the following is a specification.

This invention relates to cuspidors for use particularly in railway-cars, though capable 10 of employment in other places, as will be readily understood.

One object of the invention is to provide an article of the above character which will empty itself after use, and thus be more 15 cleanly and sanitary than those ordinarily employed; furthermore, being normally closed and out of the way.

A further object is to provide a structure the various elements of which are extremely 20 simple and so arranged that they may be readily examined should they from any cause become deranged.

The preferred embodiment of the invention is fully illustrated in the accompanying drawings, wherein—

Figure 1 is a perspective view of the cuspidor when in position in a floor. Fig. 2 is a side elevation of the same, a portion being shown in section. Fig. 3 is a vertical sectional view through the cuspidor. Fig. 4 is a bottom plan view, and Fig. 5 is a detail sectional view through one of the depending ears.

Similar numerals of reference indicate corresponding parts in all the figures of the drawings.

In this embodiment of the invention a base-plate 10 is employed that inclines downwardly and converges to a central opening 40 11, thus constituting a hopper that is in the form of an inverted cone, said plate being furthermore provided with a peripheral horizontal flange 12, having openings 13 there-through, designed to receive suitable fasten-45 ing-screws, as 14. The plate is provided on its under side with depending ears 15, which are located on opposite sides of the opening 11 and have journal-seats 16 in their lower ends, which seats are covered by bearing-blocks 17, secured to the lower ends of the ears by means of screws, as 18.

A cup 19 is revolvably mounted beneath the

opening 11, said cup being spherical in form and having gudgeons 20, journaled in the seats 16, one of the gudgeons being provided 55 with a pinion 21, located outside of the adjacent ear 15. The opening or mouth of the cup is preferably equal in size to the opening 11, with which it is arranged to aline when the cup is revolved, as will be readily understood. The means for rotating the cup is as follows: The base-plate 10 is provided with a depending lug 22, the lower end of which is bifurcated, as shown at 23, and a lever 24 is pivoted intermediate its ends in the bifurcated end of the lug. The lever is provided at one end with a curved rack 25, meshing with the pinion 21 of the cup, the other end having a flat bearing portion 26. This bearing portion 26 is located directly below a de-7c pending socket 27, formed upon the edge of the base-plate, and in said socket is slidably mounted an upright stem 28, the lower end of which bears upon the flat portion 26 of the cover, the upper end having a head 29, that 75 projects above the flange 12 of the base-plate. A flat metal spring 30 is secured at one end to the under side of the base-plate and has its free end bearing against the portion of the lever carrying the rack. A stop 31 is pref-80 erably secured to the outer face of the cup 19 contiguous to its edge and is arranged to abut against the under face of the base-plate, thus limiting the movement of said cup.

As shown in Fig. 1, when the cuspidor is 85 to be arranged in a floor the upper face of the flange 12 is made flush therewith and the base-plate is fastened by means of the screws 14. When a person desires to use the article, it is only necessary for him to press down-90 wardly with his foot upon the head 29 of the stem, whereupon the cup will be rotated to bring its mouth into alinement with the opening 11 of the hopper. As soon as the pressure upon the stem is relieved the spring 30, 95 acting upon the lever, will depress the end carrying the rack, and thus invert the cup, discharging the contents thereof. It will be evident that the structure may be placed in the top of a box or other receptacle, and the 100 invention is therefore not limited to its position in a floor, though it is designed primarily for employment in this relation, as it is completely out of the way. Should it be-

come desirable to examine the various elements, it is only necessary to remove the fastening-screws and invert the base-plate, whereupon said elements will be exposed in their operative relation, as they are all attached to said base-plate. It will thus be seen that an extremely-simple article is provided, which is more cleanly than those ordinarily in use and occupies comparatively little space. The parts, furthermore, are extremely simple and are so associated that there is little chance of derangement.

From the foregoing it is thought that the construction, operation, and many advantages of the herein-described invention will be apparent to those skilled in the art without further description, and it will be understood that various changes in the size, shape and proportion, and minor details of construction may be resorted to without departing from the spirit or sacrificing any of the advantages of the invention. For instance, if it is found desirable the cup instead of being normally inverted might be arranged with its mouth normally in alignment with the opening and be inverted by depressing the stem. This arrangement can be readily accomplished by disengaging the rack from the pinion and rotating said pinion, after which it is again placed in mesh with the rack.

Having thus described my invention, what I claim as new, and desire to secure by Letters Patent, is—

35 1. As an article of manufacture, a cuspidor comprising in combination, a floor-plate in the form of a downwardly-inclined hopper having an opening, a semispherical ball-cup journaled on and carried by the under side 40 of the hopper and arranged below the opening, a lever fulcrumed between its ends upon the under side of the hopper and carried thereby and having an engagement at one end with the cup, and an actuating device 45 engaged with the free end of the lever and passing through and carried by the hopper contiguous to its edge.

2. As an article of manufacture, a cuspidor, comprising in combination, a base-plate having an opening therethrough, depending journal-bearings located on opposite sides of the opening, a cup revolvably journaled in the bearings beneath the opening, a lug depending from the plate, a lever pivoted to the lug 55 and having a connection with the cup to revolve the same, and an actuating-stem having an engagement with the lever and projecting above the plate.

3. As an article of manufacture, a cuspidor, 60 comprising in combination, a base-plate hav-

ing an opening therethrough, a cup revolvably mounted beneath the opening and having a pinion, a lug depending from the plate, a lever pivoted intermediate its ends to the lug and having a rack at one end that engages the pinion, and an actuating-stem slidably passed through the plate and engaging the other end of the lever.

4. As an article of manufacture, a cuspidor, 65 comprising in combination, a base-plate having an opening therethrough, a cup revolvably mounted beneath the opening and having a pinion, a lug depending from the plate, a lever pivoted intermediate its ends to the lug and having a rack at one end that engages the pinion, an actuating-stem slidably passed 70 through the plate and engaging the other end of the lever, and a spring attached at one end to the under side of the plate and having its free end bearing against the lever.

5. As an article of manufacture, a cuspidor, comprising in combination, an inverted-cone-shaped hopper provided with a central opening and a peripheral flange, a cup journaled beneath the opening and having a pinion, 85 said cup being also provided with a stop arranged to engage the hopper-wall, a lug depending from the under side of the hopper, a lever pivoted intermediate its ends to the lug and having a rack at one end that engages the pinion, an upright actuating-stem slidably 90 passed through the flange of the hopper and bearing upon the other end of the lever, and a flat spring attached at one end to the under side of the hopper and having its free end bearing against the lever.

6. As an article of manufacture, a cuspidor, comprising in combination, a floor-plate in the form of a downwardly-inclined hopper having a peripheral flange and a central opening, said flange being provided with a depending socket, a ball-cup journaled upon and carried by the under side of the hopper and located below the opening, said cup having a pinion, a lever pivoted between its ends 100 to the under side of the hopper and located in angular relation to the axis of the cup, a rack located on one end of the lever and meshing with the pinion of the cup, and an actuating-pin mounted in the socket of the flange 105 and coacting with the end of the lever opposite the rack.

In testimony that I claim the foregoing as my own I have hereto affixed my signature in the presence of two witnesses.

CHARLES ELMER BERTELS.
